(57) CLAIM

The ornamental design for an emergency address marker, as shown and described.

DESCRIPTION

FIG. 1 is a front perspective view of an emergency address marker showing my new design:

FIG. 2 is a rear view thereof;

FIG. 3 is a fragmentary exploded view of the bottom portion thereof:

FIG. 4 is a top perspective view of the strike plate portion thereof, shown removed from the emergency address marker for ease of disclosure; and,

FIG. 5 is an enlarged fragmentary perspective view of the bottom portion of the emergency address marker shown in FIG. 2.

The broken lines in FIG. 1 represent unclaimed subject matter.
